US0D1058527S

(12) **United States Design Patent** (10) Patent No.: **US D1,058,527 S**
(45) Date of Patent: ** *Jan. 21, 2025

(54) **TELEVISION RECEIVER**

(71) Applicant: **LG ELECTRONICS INC.**, Seoul (KR)

(72) Inventors: **Jiwon Park**, Seoul (KR); **Yongseok Kim**, Seoul (KR); **Jaewon Oh**, Seoul (KR)

(73) Assignee: **LG ELECTRONICS INC.**, Seoul (KR)

(*) Notice: This patent is subject to a terminal disclaimer.

(**) Term: **15 Years**

(21) Appl. No.: **35/519,567**

(22) Filed: **Nov. 10, 2023**

(80) **Hague Agreement Data**

Int. Filing Date: **Nov. 10, 2023**

Int. Reg. No.: **DM/234040**

Int. Reg. Date: **Nov. 10, 2023**

Int. Reg. Pub. Date: **Dec. 29, 2023**

(30) **Foreign Application Priority Data**

Jun. 22, 2023 (KR) 30-2023-0024083
